DESIGN FOR A COMBINED CARBONATING AND DISPENSING RECEPTACLE FOR LIQUIDS

Carl F. Lozon, Massillon, Ohio

Application July 28, 1936, Serial No. 64,101

Term of patent 14 years

To all whom it may concern:

Be it known that I, Carl F. Lozon, a citizen of the United States, residing at Massillon, in the county of Stark and State of Ohio, have invented a new, original, and ornamental Design for a Combined Carbonating and Dispensing Receptacle for Liquids, of which the following is a specification, reference being had to the accompanying drawing, forming part thereof, in which

Fig. 1 is an elevational view of the article, showing my new design; and

Fig. 2 is a top plan view thereof.

I claim:

The ornamental design for a combined carbonating and dispensing receptacle for liquids, substantially as shown.

CARL F. LOZON.
